UNITED STATES PATENT OFFICE.

HENRY D. JAMES, OF PITTSBURG, PENNSYLVANIA, ASSIGNOR, BY MESNE ASSIGNMENTS, TO WESTINGHOUSE ELECTRIC & MANUFACTURING COMPANY, OF EAST PITTSBURG, PENNSYLVANIA, A CORPORATION OF PENNSYLVANIA.

ELECTRIC-CIRCUIT CONTROLLER.

947,336.

Specification of Letters Patent.

Patented Jan. 25, 1910.

Application filed April 10, 1908. Serial No. 426,341.

To all whom it may concern:

Be it known that I, HENRY D. JAMES, a citizen of the United States, and a resident of Pittsburgh, in the county of Allegheny and State of Pennsylvania, have invented a new and useful Improvement in Electric-Circuit Controllers, of which the following is a specification.

My invention relates to electric circuit controllers and it has special reference to such controllers as are adapted to effect the starting of alternating current electric motors in connection with auto-transformers or other means for reducing the voltage initially applied to the motor windings.

The object of my invention is to provide a device of the class above indicated that shall be simple and durable in construction and adapted for the control of relatively low-voltage circuits that are traversed by very large electric currents.

In order to effect the aforesaid objective results and to provide other improvements, as hereinafter pointed out, I have employed a switching device that comprises, in general, two groups of movable contact members both of which are electrically connected by flexible shunts to a group of stationary contact terminals and a single operating handle lever which may be moved in one direction or the other from its "off" position to effect the engagement, of one group of movable members, with a coöperating group of stationary contact members.

In order to enable the controller to carry very large electric currents continuously without over-heating, the group of movable members which effect circuit connections for motor running comprise wedge shaped bridging contact members that are closed last when the controller is moved to its motor-running position and are opened first when it is returned to its "off" position and which are so arranged as to provide low-resistance shunt circuits to the flexible conductors connecting the motor-running group of movable members to the stationary group of contact terminals.

Figure 1 of the accompanying drawings is a side elevation, partially in section, of a controller constructed in accordance with my invention, Fig. 2 is a front elevation of the device shown in Fig. 1, certain of the parts being broken away to disclose more

fully the contact members, and Fig. 3 is a diagrammatic view showing the circuit connections of a motor control system embodying my improved starting switch. Figs. 4, 5, 6, 7, 8, 9, 10, 11, and 12 are detail views of the operation levers and the contact members of the device shown in Figs. 1 and 2.

Referring to the drawings, the device here illustrated comprises a metal frame 1, which may be supported substantially in a horizontal plane by means of projecting ears 2, a plurality of stationary contact members comprising groups 3, 4, and 5, a plurality of movable contact members comprising groups 6 and 7, overload release magnets 8 and 9, an operating handle lever 10 and a suitable gear mechanism 11 by which the action of the handle lever may be transmitted to the groups of movable contact members.

The bracket or casting 1 is provided with pairs of parallel bearing projections 12, 13, 14, and 15 and a plurality of holes 16 to receive substantially cylindrical screw threaded terminal rods 17 with which the stationary contact members are provided. The terminal rods 17 are insulated from the plate 1 by means of bushings 18 and washers 19 and are firmly secured thereto by means of set nuts 20, the lower extremities of the contact members being enlarged to support laminated contact terminals and to provide engaging surfaces which coöperate with the movable contact members, as hereinafter pointed out. The group 3 of stationary contact members comprises a plurality of members *a*, *b*, *c*, and *d*, arranged substantially in a straight line, each having a body member 21, with a horizontal plane bottom surface to which contact blocks 22 are secured by means of screws 23. The group 6 of movable contact members is composed of a plurality of substantially cylindrical contact blocks 24 which are divided into sets of four that respectively coöperate with the stationary contact blocks 22 of the members *a*, *b*, *c*, and *d* and are resiliently supported between horizontal cross strips or plates 25 and 26. The plates or cross strips 25 and 26 are supported by a pair of insulating strips 27 and 28 arranged in parallel and vertical planes between which the contact blocks 24 are disposed. The resilient connection between the contact blocks 24 and the supporting frame, which is composed of

the parts 25, 26, 27, and 28, is effected by means of springs 29 that are coiled about shanks 30 of the blocks and are interposed between their bodies and the cross strips 26.

5 The movement of the blocks is limited by nuts 31 which are screwed upon the lower ends of the shanks after they are thrust through suitable holes in the plate 26.

10 The group 4 of stationary contact members comprises a plurality of members *e*, *f*, *g*, and *h* having arms 32 that are provided with lateral projections 33 to which laminated contact members 34 are secured, said arms being connected to the ends of the shanks 30 by means of flexible conductors 35 which are secured to the ends of the arms by bolts 36 and to the shanks by the nuts 31.

15 The group 5 of stationary contact members comprises a plurality of members *i*, *j*, *k*, and *l* which are similar to those of the group 3 except that they are provided with lateral projections 37 to which laminated contact members 38, corresponding to the members 34, are secured.

20 The group 7 of movable contact members comprises a horizontal rod or bar 39 of insulating material to which are secured wedge-shaped bridging contact members 40 that engage beveled surfaces 41 of the laminated contact members 34 and 38. Plates 42 are affixed to the upper and lower surfaces of the horizontal rod 39 and project laterally over one side to support a set of arc-breaking contact members 43 which are similar to the contact members 24 and are adapted to make and break the circuits finally established through bridging contact member 40 and the laminated contact members 34 and 38, when the controller is in its motor-running position. The laminated contact members comprise a plurality of plates or strips of copper or other conducting material which are slightly separated from each other by relatively short spacing strips 44 so that the contact end of each strip is permitted a slight independent adjustment. The arc-breaking contact members 43 are connected to the arms 32 by flexible conductors 45 which are of sufficient length to provide for an adequate movement of the group 7.

25 The overload release magnets 8 and 9 are of a well known type and comprise stationary core members 46 and movable core members 47 which are influenced by magnet windings 48 and an adjusting lever 50 which is pivotally supported upon a stationary shaft 51 and is adapted to effect a simultaneous adjustment of the air gap which is provided between the stationary and movable core members.

30 The gear mechanism 11 comprises a pair of toggle levers 52 and 53 which are pivoted on a stationary shaft 54, an actuating lever 55, a pair of short links 56 and 57 which are joined together and are connected at one end to the projection 15, a second pair of short links 58 and 59 which are similarly disposed relative to the projection 14, links 60 and 61 which connect the free ends of the two pairs of short links to the projections 12 and 13 70 and links 62 and 63 which connect the ends of the toggle levers 52 and 53 to the junction points of the short links. The points of connection between the links 60 and 61 and the short links 57 and 59 are respectively joined to the groups 6 and 7 of movable contact members by means of rods 64 and 65. The toggle levers 52 and 53 are provided with projections 66 and 67 having radial surfaces 68 which extend in relatively opposite directions from their axes of rotation and substantially in alignment with the arms of the levers. The lever 53 is further provided with a projection 69 which limits its movement in one direction, as hereinafter pointed out, and the arms of both levers are bifurcated to receive the ends of the links 62 and 63.

35 The actuating lever 55 is provided with lateral projections 70 and 71 having radial 90 surfaces 72 that engage the surfaces 68 on the toggle levers, the arrangement of the parts being such that when the actuating lever is rotated through a relatively short angle in one direction, the toggle lever 53 95 will be rotated without imparting any movement to the toggle lever 52 and when the actuating lever is rotated in the opposite direction the toggle lever 52 will be rotated independently of the toggle lever 53. The handle lever 10 is also pivotally mounted on the shaft 54 and comprises a pair of parallel strips 73 which are separated by spacing blocks 74 so that the actuating lever 55 may extend into the space between them. The 100 actuating lever and the handle lever are operatively connected together by means of a latch 75 which is connected to a tripping lever 76 by means of a link 77 and which is normally held in engagement with the extremity of the actuating lever by means of a spring 78. When the handle lever is raised to move the group 6 of movable contact members into engagement with its co-operating stationary members, no means are 110 provided for locking the controller and it is, therefore, necessary for an attendant to manually hold the switch in this, its motor-starting, position. When the motor has accelerated, the switch may be moved from the 115 "off" position, which it assumes, when released, by reason of the action of gravity on the movable contact members, and from thence to the running position in which a projection 79 on the handle lever is engaged 120 by a latch 80.

125 When the controller occupies the running position, projections 81 of the tripping lever 76 are in the line of action of the hammer rods 82 of the release magnets 8 and 9 and, 130

when the controller occupies its other positions, the projections 81 are carried out of this line so that the overload release magnet may be suitably designed for protecting the 5 motor circuits under normal operating conditions without interfering with the application of relatively large current values during the starting period. If it is desired to release the controller from its running position, pressure may be applied to the outer end of the push pin 83 which extends slightly beyond the outer end of the handle lever and the inner end of which may engage the latch 80 and release it from the projection 15 79. The push pin is normally freed from the latch by means of a spring 84.

The operation of the device, with special reference to the gear mechanism 11, is as follows: Assuming that the controller occupies its "off" position, as illustrated in the drawings, it will be observed that the short links 56 and 57, and 58 and 59 form acute angles with each other so that the groups 6 and 7 of movable contact members occupy 20 their positions of maximum separation from the stationary contact members. Links 60 and 61 serve to guide the upper ends of the toggles formed by the links by connecting them to the stationary projections 12 and 25 13. If the handle lever is now moved upwardly the toggle lever 52 is rotatively moved in a clockwise direction by reason of the engagement of the surface 72 on the projection 71 of the operating lever with the 30 surface 68 on the projection 66 of the toggle lever. The said rotative movement creates a pressure, through the link 63, against the vertex of the acute angle formed by the links 58 and 59 and causes them to move into the 35 same straight line, thereby raising the rod 65 and the group 6 of movable contact members. This movement of the operating lever causes a separation between the surface 68 on the projection 67 of the toggle lever 52 40 but does not cause any movement of this toggle lever. If the handle lever is now returned to its "off" position and rotated through a similar angle in the opposite direction, the toggle lever will be rotated 45 in a counter-clockwise direction and a force of tension will be exerted on the link 62 which will cause the toggle formed between the links 56 and 57 to straighten and the group 7 of movable contact members to be 50 raised.

The circuit connections for the device, when employed in a system of control for electric motors, are illustrated in Fig. 3 to which special reference may now be had. 55 Alternating current energy is supplied to an electric motor 85, from any suitable source, through conductors 86, 87, 88, and 89, the control switch of my present invention being employed to govern the motor circuits.

60 Assuming that the control switch occu-

pies its "off" position α , if it is now moved to its motor starting position γ , which may be accomplished by raising the operating handle lever as hereinbefore described, circuit connections will be established as follows: from an intermediate point 90 in a starting transformer 91, which is connected across the circuit 86-87, through a conductor 92, contact members c and g , which are now joined electrically by a movable contact member and the shunts 35, and a conductor 93 to a terminal 94 of the motor, circuit being completed from terminal 95 through conductor 96, contact members h and d , and conductor 97 to the conductor 86. A second circuit is similarly established from an intermediate point of a transformer 98, which is connected across the circuit 88-89, so that a relatively low-voltage poly-phase electric current is supplied to the 85 motor for starting.

It will be observed that the overload release magnet windings 48 are omitted from the starting circuits, in accordance with the usual practice. If the control switch is now moved to occupy position α circuits will be established from the line conductors 87 and 88 through conductors 99 and 100, magnet windings 9 and 8, contact members $j-f$ and $k-g$ and conductors 93 and 101 to the motor terminals 94 and 102, the two circuits being completed from motor terminals 95 and 103 through conductors 96 and 104, contact members h and l , and e and i and conductors 97 and 105 to line conductors 86 and 89.

The arrangement of contact members and the circuit connections of the system may, of course, be adapted for starting either two or three-phase motors and it is to be understood that various structural modifications may be effected in the device illustrated without departing from the spirit and scope of my invention.

I claim as my invention:

1. In a controller, the combination with a stationary frame or bracket, a plurality of contact members secured thereto and insulated and suspended therefrom, vertical rods or bars extending through the frame, and movable contact-bearing members secured to the lower ends of the rods or bars and adapted to be moved vertically into engagement with the stationary contact members, of means for operating the vertical rods or bars, said means comprising a pair of links forming a toggle joint connection between their outer ends and a stationary pivotal point, an operating lever and a relatively long connecting link interposed between the toggle joint and the operating lever.

2. In a controller, the combination with a stationary frame or bracket, a plurality of main and auxiliary contact members se-

110

115

120

125

130

- cured thereto and insulated and suspended therefrom, and vertical rods or bars projecting through the frame, of movable contact-bearing members secured to the lower 5 ends of the rods or bars and adapted to be moved vertically into engagement with the stationary members, said movable members being provided with bridging contact members to coöperate with the main stationary 10 contact members, yieldingly supported arc-breaking contact members coöoperating with the auxiliary contact members, and flexible connections between the main stationary contact members and the movable arc-breaking 15 contact members.
3. In a controller for electric circuits, the combination with three groups of main stationary contact members, one composed of rigid and the other two of yielding contact members, a group of rigid auxiliary contact members and a plurality of contact arms extending downwardly from one group of yielding contact members, of two contact bearing members, one provided with yielding contacts to coöperate with the rigid main contacts and the other provided with rigid contacts for bridging the yielding contact members and yielding contacts for co-operating with the rigid auxiliary members, 25 said yielding movable contact members being connected by flexible shunts to said contact arms.
4. In a controller for electric circuits, the combination with a stationary supporting 30 bracket, three groups of stationary contact members secured thereto and insulated therefrom, movable contact members comprising two groups and flexible connections between one of the groups of stationary members and both of the groups of movable 35
- 40

members, rods or bars extending through the stationary bracket and adapted to move the movable members into and out of engagement with the stationary members, of an operating gear mechanism comprising a 45 pair of short links secured to the upper extremity of each of the rods or bars and pivotally connected to the stationary bracket, an operating lever rotatably supported from the bracket and connected to the toggle 50 joint connection formed at the juncture of the two short links by means of relatively long horizontal connecting links.

5. In a controller for electric circuits, the combination with a plurality of stationary 55 contact members comprising three groups, movable contact members comprising two groups and flexible connections between one of the groups of stationary members and both of the groups of movable members, of 60 means for short-circuiting the flexible connection of one of the groups of movable members.

6. In a controller for electric circuits, the combination with a plurality of stationary 65 contact members, a group of movable motor-starting contact members, and a group of movable motor-running contact members, of flexible conductors connecting the movable members with a plurality of stationary 70 terminals, and means for short-circuiting the flexible conductors of the movable motor-running contact members.

In testimony whereof, I have hereunto subscribed my name this 30th day of March, 75 1908.

HENRY D. JAMES.
